United States Patent Office

Des. 204,006
Patented Mar. 8, 1966

204,006

FLOWER STAND

Thomas H. Reed, 114 Seavey Circle, Sacramento, Calif.

Filed June 15, 1965, Ser. No. 85,743

Term of patent 14 years

(Cl. D35—3)

FIG. 1

FIG. 2

I claim:

The ornamental design for a flower stand, substantially as shown.
